Edwin P. Van Sciver, Philadelphia, Pa., assignor
of one-third to Earl T. Van Sciver, Glenside,
and one-third to Wesley J. Van Sciver, Wynne-
wood, Pa.

Application March 3, 1948, Serial No. 144,882

Term of patent 14 years

(Cl. D34—2)

To all whom it may concern:

Be it known that I, Edwin P. Van Sciver, a citizen of the United States, residing in Philadelphia, Philadelphia County, Pennsylvania, have invented a new, original, and ornamental Design for an Aquatic Toy, of which the following is a specification, reference being had to the accompanying drawing, forming a part thereof, in which:

Fig. 1 is a side elevational view of an aquatic toy showing my new design;

Fig. 2 is a front end elevational view thereof;

Fig. 3 is a top plan view thereof;

Fig. 4 is a sectional view on line 4—4, Fig. 1; and

Fig. 5 is a sectional view on line 5—5, Fig. 1.

I claim:

The ornamental design for an aquatic toy, substantially as shown.

EDWIN P. VAN SCIVER.
